UNITED STATES PATENT OFFICE

EDWARD F. REED, OF NEOSHO, MISSOURI

DESIGN FOR A CABINET

Application filed May 19, 1931. Serial No. 39,909. Term of patent 7 years.

To all whom it may concern:

Be it known that I, EDWARD F. REED, a citizen of the United States, residing at Neosho, in the county of Newton and State of Missouri, have invented a new, original, and ornamental Design for Cabinet, of which the following is a specification, reference being had to the accompanying drawings, forming part thereof.

I claim:—

The ornamental design for a cabinet as shown.

EDWARD F. REED.
